UNITED STATES PATENT OFFICE.

LOTHIAN KERR SCOTT, OF FARNBOROUGH, ENGLAND.

SIGHT FOR ORDNANCE.

SPECIFICATION forming part of Letters Patent No. 712,420, dated October 28, 1902.

Application filed October 5, 1901. Serial No. 77,739. (No model.)

To all whom it may concern:

Be it known that I, LOTHIAN KERR SCOTT, C. B., lieutenant-colonel late royal engineers, a subject of the King of Great Britain, residing at Forest Lodge, Farnborough, in the county of Hants, England, have invented certain new and useful Improvements Relating to Sights for Ordnance, of which the following is a specification.

10 This invention relates to improvements in gun-sights of the kind described in the specification of my United States of America Patent No. 658,287, dated September 18, 1900, in which all that need be done when laying 15 the gun is to bring the line of sight upon the object aimed at, no matter at what range the said object may be, the sight when moved with the gun effecting automatically the adjustment required for range, provided an 20 initial adjustment according to the position of the gun is properly made.

According to my present invention I have arranged the automatic sight to be carried by some standing part of the gun-carriage or 25 support or to a loose arm of the duplex elevating-gear and not by the trunnion or other part of the gun or its cradle, and to be operated by a lever or other device connected to the elevating-gear of the gun, and I therefore 30 fore term this sight a "gun-carriage" sight. This gun-carriage sight can be operated at some distance from the gun itself, and may be therefore readily adapted to disappearing guns, and to naval guns on revolving platforms, and to guns supplied with the duplex 35 elevating-gear. I also provide the automatic sighting mechanism with a curve adapted to give automatically to the sight the necessary horizontal correction in deflection for 40 "drift"—i. e., the deviation of the shot due to the rifling of the gun.

Referring to the drawings, Figure 1 is a side elevation of the gun-carriage sight applied to a disappearing gun. Fig. 1^a is a detail plan of the means for automatically giving to the sight the correction for drift. Fig. 1^b is an end view of Fig. 1^a looking in the direction of the arrow. Fig. 2 is an end view, partly in section, of the apparatus 50 shown in Fig. 1. Fig. 3 is a plan view of the free end of the range-curve and its bracket shown in Fig. 1. Fig. 4 is a side elevation,

partly in section, of part of the range-curve frame and an interchangeable adjustable curve. Fig. 5 is a detail view of a rod shown 55 at right angles to Fig. 4. Fig. 6 is a modification of the range-curve shown in Fig. 4. Fig. 7 is a side elevation of the sighting apparatus applied to a non-disappearing gun. Fig. 8 is an enlarged view of part of the apparatus shown in Fig. 7, one of the range-curve screws being shown in vertical section. Fig. 9 is a detail of a modification of the apparatus shown in Fig. 8. Fig. 10 is a plan of part of the range-curve frame and the device 60 for automatically giving to the sight the necessary correction for drift. Fig. 11 is a view of a detail of the mechanism shown in Figs. 7 and 8.

Referring to Fig. 1, 1 is a telescope-sight 70 carried by a range-curve frame or sight-bar 2, pivoted at 3 to a bracket 4, centered around a pivot 5, carried by a standard 6, fixed to the floor of a revolving platform or turret or some part of the gun-carriage, which moves in a 75 horizontal plane with the gun.

9 10 are set-screws carried by the standard 6 for leveling the bracket 4 for adjusting the sight and for correcting for fore-and-aft dip in the gun-platform. 80

11 is a clinometer-level.

The range-curve frame 2 is provided with a projecting piece 12, which is adapted to slide in a groove 13 in the bracket 4. To the piece 12 is attached a vernier to read to minutes and seconds the graduated edge of the bracket 4. When vertically adjusted in the required position with respect to the bracket 4, either in order to form the range-curve, as hereinafter described, or to set the sight when used as an ordinary sight to any required elevation, the frame 2 can be clamped by means of a screw 14. 85

The frame 2 is so constructed that it may be employed with a range-curve composed of a number of double-acting screws, as described in the specification of my prior patent, No. 658,287, and is for this purpose provided with the necessary number of perforations for the reception of such screws. On the right-hand side of the frame shown in Fig. 1 is a bridging-plate 15, upon which the ends of the double-acting screws rest. The frame 2 is also provided with extensions 16 16, having lon- 90 100

itudinal channels adapted to receive the bent-up ends of a single rigid range-curve, such as 17, Figs. 1 and 4. The curve 17 is provided at its center with a slot 18, with 5 which the T-shaped end of a rod 19 engages. The opposite end of the rod 19 passes through a cylindrical space 20 in the frame 2 and carries a piston 21, adapted to slide in said space. The top of the rod 19 is provided with a push-10 piece 22, and 23 is a spring, the ends of which bear upon the lower side of the piston 21 and the bottom of the cylinder 20.

24 24 are adjusting-screws which engage with suitable screw-threaded holes in the 15 frame 2 and have their ends bearing upon the turned-up end of the curve 17. These screws 24 serve to adjust the curve 17 against the pressure of the spring 23 for correcting the position of the curve 17 for "errors of the 20 day"—that is to say, for errors due to the quality of the powder and for "fore-and-aft" wind correction.

25 is a crank "sight-lever" having its pivot 5 carried by the standard 6. The longer arm 25 of this lever carries a roller or traveler 26, upon which the range-curve rests, and the shorter arm of said lever is connected by an adjustable screw-coupling 27 to a rod 27^a, pivoted to the gun-elevating gear-block 28. The 30 gun-elevating arm 28^a is also pivoted to the block 28, which is adapted to reciprocate in a groove 28^b to elevate or depress the gun, as is well understood. The bracket 4 must be centered around the axis of the lever-pivot 5 35 and must be capable of being turned by the screws 9 and 10 at will either in conjunction with or independently of the crank-lever 25, first, for correcting for fore-and-aft dip in the platform and for enabling the sight 40 and lever to be depressed together onto the buoy at the nearest range without disturbing the lever from the zero position on the range-curve, the coupling 27 having been previously released; second, for the adjustment of the 45 lever to the zero on the range-curve independently of the bracket, both as hereinafter described.

50 The bracket 4 is provided with a segmental or arc-shaped groove 29, in which a vernier 30, carried by the lever 25, is adapted to slide. Both edges of the groove 29 are graduated, the upper edge, say, in degrees and the lower edge, say, in yards, so that the vernier 30 indicates both the elevation of the gun and also 55 the range.

The sighting apparatus may also carry an ordinary Scott telescopic gun-sight, as shown in broken lines at 31, if required, instead of the telescopic sight 1. This Scott sight will 60 give the correction for lateral inequality of the gun-platform.

The telescopic sight 1 is pivoted at 32 and is provided with a forward extension 32^a, having a drift curve or cam 34, held against a 65 stationary pin or boss 32^b, carried by the bracket 4.

33 is a spring which holds the drift-curve 34 against the pin 32^b.

35 is a deflection-screw working in this piece, automatically moved for drift, whereby 70 the sight 1 may independently of the curve 34 be given the necessary horizontal deflection for various causes, such as wind or speed of moving target across the range other than drift which is corrected automatically. 75

Fig. 6 illustrates a similar range-curve and range-curve frame to Fig. 4; but in this case screws 36 for adjusting the curve 17 are each provided with a nut 37 for regulating the screw to correct errors of the day and with 80 a head 38 for regulating the screw in accordance with the state of the tide, if firing at objects at sea. The screw-coupling 27 permits of the adjustment of the roller 26 in the required position on the range-curve without 85 altering the elevation of the gun. The screws 9 and 10 are employed in conjunction with the screw-coupling 27 for correcting the positions of the bracket 4 and the lever 25 for any accidental fore-and-aft dip of the gun-plate- 90 form, &c.

The clinometer-level 11, which must be permanently set level and not disturbed after the bracket 4 has been correctly adjusted, indicates whether the gun-platform is level. 95

After the preliminary adjustments of the automatic sighting mechanism have been made as the gun is elevated or depressed the necessary angular adjustment between the line of sight and the longitudinal axis of the 100 gun for range is given automatically to the sight 1 by the lever 25, which is moved about its pivot 5 as the block 28 is raised or lowered in the groove 28^b for elevating or depressing the gun. The movement of the lever 25 in 105 addition to moving the traveler 26 along the range-curve causes the vernier 30 to register both the elevation of the gun and the range of the object fired at for one fixed height of tide. If the roller is accidentally caused to 110 leave the range-curve by the over elevation or depression of the gun, the frame 2 is supported by a spring 39, carried by the frame 4.

To construct the adjustable range-curve for the "carriage-sight," Fig. 1, supposing the 115 height of the gun above the sea to be one hundred feet and that the angles of depression of the telescope and the elevations of the gun are known for all ranges and that the nearest range of the gun has been fixed at, 120 say, one thousand yards, first set the sight 1 and the Scott telescopic gun-sight 31 to zero elevation and deflection; second, depress the sight bar or frame 2 (whose longitudinal axis is parallel to the zero axis of the telescope) 125 through the angle of depression required at a height of one hundred feet to make the cross-wires of the telescopic sight 1 or the pointer of 31 cut the sea at either high water or low water or mean water, as may be required, at one thousand yards range, as indicated by a buoy or otherwise, the angle being 130

read off the graduated edge of the bracket 4 by the vernier, and temporarily clamp the sight-bar in that position by the screw 14; third, set the roller end of the lever 25 under the end 5 of the double-action screw 36 and bring the bridging-plate 15 of the range-curve into contact with the roller 26 by turning the head of the screw 36; fourth, give the gun the required elevation to strike the water-line of the buoy 10 at one thousand yards; fifth, connect the short end of the lever 25 to the rod 27^a, which is pivoted to the block 28, as being the point 15 of the elevating-gear which is the least likely to create loss of time between the movement of the gun and that of the lever, taking care that the angle of depression of the sight-bar has in no way been altered; sixth, unclamp the sight-bar by loosening the nut 14. This forms the zero-point of the range-curve, and 20 by repeating the above operations for every hundred yards of range the range-curve for one hundred feet above the sea at high tide, or low tide, or mean tide, as the case may be, is obtained. It is obvious that the bridging- 25 plate may then be copied for the production of a rigid range-curve.

The special advantage of the adjustable curve is that the same automatic sight can be used at any height above the sea and that 30 corrections for all errors for tide, &c., can be readily and accurately made all along the curve before firing, thereby rendering the working of the sight truly automatic.

If interchangeable rigid curves are preferred, a different curve would be employed, 35 say, for each foot of tide.

When it is required to substitute a rigid range-curve, such as 17, for the compound range-curve, all the double-acting screws, with 40 the exception of the two end ones 36, are removed from the frame 2. The bent-up ends of a rigid curve 17 are then inserted in the extensions 16 on the frame 2, the push-piece 22 is depressed to lower the T-shaped end of 45 the rod 19 into engagement with the slot 18, and the push-piece 22 is then released, so as to permit the spring 23 to bring the ends of the curve into contact with the screws 24 or 36.

If interchangeable curves are to be employed for each foot of tide, the two end 50 screws need only be single-acting screws, such as 24, for making the necessary correction for errors of the day.

If one rigid curve only is to be used for all 55 heights of the tide, two double-acting screws, such as 36, for making the necessary corrections both for tide and for errors of the day, must be employed.

If the nearest range of the gun is one thousand yards, say, at high tide, a shot should be fired at this range, and the point where the shot strikes should be carefully marked by depressing the zero-line of sight of the telescope onto it and clamping it there by 65 means of the screw 14. The clinometer-level should then be leveled and the position of the lever 25 marked on the arc 29. A buoy

should be placed at this point for future reference, so that if the gun-platform remains level whenever the zero "line of sight" of the 70 telescope-sight 1 is turned on the water-line of the buoy at high tide, say, the lever 25 will indicate the same elevation on the arc 29.

To use the carriage-sight, Fig. 1, as an ordinary sight, the range must first be found by depressing the sight with its tidal and error-of-the-day screws set to zero onto the water-line of the target by the elevating-gear of the gun and allowance made for the rise or fall of tide with reference to the datum height of 80 tide assumed. The automatic sighting range-curve must then be removed and replaced by a range-curve of such curvature as to cause the line of sight of the telescope to move parallel with the axis of the gun when elevated 85 or depressed. The telescopic sight 31 is then set to the range found and, if necessary, corrected for tide, and the gun is laid in the ordinary way by its elevating-gear.

When the automatic sight is to be used as 90 a range-finder as well, the range may be indicated in yards either on the arc 29 or on a rigid range-curve, such as 17. The position of the lever 25 or of the roller 26 will then indicate the range, requiring, however, the 95 minus or plus correction for rise or fall of tide.

Examples: If a graduated rigid range-curve is employed for indicating the range at, say, one hundred feet above the sea, it will only 100 indicate the range correctly at that particular state of the tide. If the reading of such rigid curve is, say, one thousand yards for one hundred feet above the sea at high tide, the reading for one hundred and one feet above the 105 sea should be one thousand plus ten or one thousand and ten yards, so that all that is necessary in this case is to add to the range found a one hundredth part of the range for every foot of fall of the tide and to subtract that 110 amount from the range for every foot of rise of the tide.

General formula for finding the amount to be added to or subtracted from the range given by the sight for every foot of fall or 115 rise of the tide below or above the assumed datum level for which the cam-curve has been constructed: Let h equal height of gun above the sea in feet, R equal range of target, say, at high tide (datum level) in yards, f equal number of feet of rise or fall of tide above or below datum level. The increment of range to be added to the range given by the sight at high tide due to f feet fall of tide is $\left(\frac{f}{h}\right)$ and the true range is 125

$$\left(R + \frac{f}{h} R\right) \text{ equals } R \left(1 + \frac{f}{h}\right).$$

Owing to the extreme sensitiveness of the 130 automatic sighting mechanism and to the disastrous effects which an inaccurate automatic sight will produce on the shooting of the gun by the slightest error in the curvature of the

range curve or cam it is essential that the layer should have at all times in combination with the automatic sighting apparatus itself the means of testing and adjusting any part of said curve. This is the reason why my automatic sighting apparatus is provided with graduated arcs and verniers, as above described, so that by having calculated tables for the angles of elevation of the gun and for the corresponding angles of depression of the line of sight for various heights above the sea-level the layer may for any point of the curve read off the angles given by the graduated arcs and compare them with the tables.

15 A great advantage of the carriage-sight is that the layer can keep his eye on the telescope and observe the point of impact of the shot with reference to the target and measure the errors in range and direction mechanically by turning the line of sight horizontally and vertically onto the point of impact by the elevation and deflection screws of the Scott sight.

20 The great advantage of connecting the shorter arm of the lever 25 to the elevating-gear block 28 is that this enables the gun to be laid while in the recumbent or loading position.

25 Referring to Figs. 7 and 8, 6 is the fixed standard carried by a pivoted gun-carriage and in which the trunnion 51 of the gun is journaled and which supports a bracket 52, carrying a worm-wheel or elevating-screw 53, gearing with a toothed sector 54 on one arm 30 of a crank-lever 55, pivoted loosely on the trunnion 51. The other arm of the lever 55 has pivoted to it a laterally-grooved block 56. 57 is a crank-lever fixed to the gun-trunnion 51 and having one of its arms provided with 35 a toothed sector 58, gearing with a worm-wheel or elevating-screw 59, carried by the lever 55. The other arm of the lever 57 has pivoted to it a lever 60, the ends of which are forked. The lever 57 also carries a bracket 40 61, provided with bearings 62, which support a rod 63, situated parallel to the longitudinal axis of the gun. Upon the rod 63 a collar 64, carrying the traveler or roller 65, is adapted to slide. The collar 64 is also provided with 45 a trunnion 66, which carries a laterally-grooved block 67. The forked ends of the lever 60 are adapted to respectively slide in the grooves of the blocks 56 and 67. The toothed elevating-sectors 58 and 54 are placed 50 at the ends of crank-levers instead of straight levers, depending from the trunnion in order to take off the teeth of said sectors the cross strain from the jump of the gun to which they would be subjected in the case of straight 55 levers. The sight bar or frame 2 is pivoted at 68 to a sleeve 69, mounted on the rod 63. The forward end of the frame 2 has a depending piece 70, which is graduated in degrees for coöperating with a vernier carried 60 by a sleeve 71, mounted on the rod 63. The sleeve 71 carries an elevating-pinion 72, which gears with teeth formed on the piece

70, for giving the adjustment for range to the sight by hand, or this adjustment of the sight by hand may be given by turning the graduated screw 63^a, which engages a screw-threaded hole in the bar 63 and bears on the bar 2, as shown in Fig. 9.

The range-curve is constructed, as above described, of a number of doubly-adjustable 75 range-curve screws bearing upon a bridging-plate which rests upon the roller or traveler 65. The telescopic sight 1 is mounted in a bracket 73, pivoted at 74 to the frame 2, so as to be capable of adjustment in a horizontal 80 plane.

74^a is a camway or slot in the forward end of the bracket 73 for engaging the end of an arm 75, fixed or clamped to the pivot 68. 76 is a spring which tends to press the side of 85 the slot or camway 74 against the end of the arm 75.

76^a is a level carried by the frame 2 at right angles to the axis of the gun.

The doubly-adjustable range-curve screws 90 preferably comprise a central screw 77, provided with a head or finger piece 78, engaging an internally-screw-threaded sleeve 79, provided with a feather or key 80, adapted to slide in a longitudinal groove or keyway 81 95 in the frame 2. The lower end of the sleeve 79 is also externally screw-threaded and carries an adjusting-nut 82. By turning the heads 78 the screw is raised or lowered for giving the necessary corrections to the range-curve for the height of the gun above the sea and for tide. By turning the nut 82 the sleeve 79, together with the screw 77, is raised or lowered for giving to the range-curve the necessary corrections for "errors of the day"— 105 that is to say, for errors due to variations in the powder and to "fore-and-aft" wind.

The sleeve 69 carries a toothed sector 83, which gears with a worm-wheel 84, journaled in a standard 85, carried by one of the bearings 62. By turning the worm 85 the range-curve and sight 1 may be turned angularly about the rod 63, and thereby leveled.

Referring to Fig. 11, which is a plan of the elevating-pinion 72 and shows also part of the 115 sleeve 71 in section, the axis of the toothed elevating-pinion 72 carries a screw-threaded drum 86, graduated in yards, say, for high water. 87 is an indicator-arm which engages with the screw-threaded drum 86 and is provided with lugs 88 to slide in guides 89.

To operate the sighting mechanism (shown in Figs. 7 and 8) automatically, the elevation-pinion 72 is moved out of engagement with the teeth on the piece 70 by an eccentric 72^a, 125 which causes the block holding the pinion 72 to slide back in a groove. When the elevating-screw 59 is then turned, the toothed sector 58 is raised or lowered. The gun, together with the rod 63, is thereby elevated or depressed, and the pivot of the lever 60 is caused to move angularly about the trunnion 51. This angular movement of the pivot of the lever 60 causes the lower forked arm of said

lever to slide in the grooves of the pivoted block 56 as said block moves about its pivot and causes the upper forked arm of said lever while similarly sliding on the pivoted block 66 to move the collar 64 and the traveler 65 along the rod 63, and thereby cause the range-curve to move about the pivot 68 as the gun is elevated or depressed, and thus give the necessary angular correction for range between the line of sight and the longitudinal axis of the gun. As the sight-bar 2 is moved vertically about the pivot 68 the camway or slot 74 slides on the free end of the fixed arm 75, and thereby moves the bracket 73 and telescopic sight 1 horizontally, so as to automatically give to the said sight the necessary lateral correction for "drift."

The sector 58 is provided with a vernier 90, to be read in connection with a scale 91, graduated in degrees on the lever 55.

To operate the sight without automatically giving it the adjustments for range and drift, the elevating-screw 53 is employed. When this elevating-screw is turned, the levers 55, 57, and 60, the gun, and the sight 1 are together elevated or depressed without giving automatically to said sight the adjustments for range and drift. 92 is a clinometer-level carried by the lever 55 and capable of being adjusted by a cam 93. By disconnecting a screw-coupling 920 the lever 60 may be disconnected from the sleeve 64 and traveler 65. For giving the corrections for range to the sight by hand the elevation-pinion 72 is moved into gear with the teeth on the piece 70. As the elevating-pinion 72 is turned the arrow on the indicator-arm 87 indicates for one height of tide only the true range in yards on the drum 86, and the vernier on the bracket 71 indicates the elevation of the gun, in degrees, for the same height of tide.

Various Uses of the Carriage-Sight, Fig. 1.

Disappearing gun.—To lay the gun, using the adjustable cam-curve:

First. By turning the head 38 of the double-action adjusting-screws, the spirals of which are graduated to each foot of rise or fall of tide, adjust the curve-plate 15 to the required curvature for the height of tide.

Second. By turning the nuts 37 of the above screws adjust the curve-plate 15 so as to increase or decrease the range according to the force and direction of the wind and force of powder. Each spiral of a nut is graduated to minutes of elevation.

Third. By the elevating-gear and traversing arrangements of the gun bring the telescopic sight onto the water-line of the target.

Fourth. Raise the gun into the firing position, fire, and, observing the shot through the sight, turn the horizontal pointer onto the point of impact (a) (with the Scott telescopic sight) by the deflection and elevation screws of the sight and (b) (with the autotelescopic sight) by the horizontal and vertical movement of the diaphragm holding the horizon-

tal pointer. This operation will give the required correction in range and direction which, through the intermediary of the nuts 37, will have to be given to the curve-plate 15 before the next round. If the target is moving from or toward the gun, the horizontal and vertical scales inside the telescope must be used to guide the layer in laying a definite amount to the right or left of it and above or below the water-line, according to the speed of the target.

Fifth. In all cases the telltale-level 11 must be level before firing. If it is not level, the platform is not level, and the bracket 4 must be adjusted level by screws 9 and 10, previously taking care to unclamp the lever 25 by clamp 27 and to reclamp it to 27^a when relevelled before using the elevating-gear of the gun.

To fire at any point of the target above the water-line. First, having laid the gun, as above described, on the water-line of the target, measure (by the vertical scale in the telescopic sight or by the deflection-scale turned into a vertical position by revolving the telescope in its bearings or by the elevation-screw of the Scott sight) the angle subtended between the water-line and the point to be fired at, and by the elevating-gear elevate the gun that amount, as indicated by the vernier 30. Then fix the point of aim by turning the pointer onto it by its own screws.

To continue the firing, lay in future on that point, and the gun will automatically receive the required elevation to hit it. This change of fire from one point to another of the target is done very much more readily when the duplex elevating-gear is brought into use, such as is shown.

To use the carriage-sight, Fig. 1, as an ordinary sight:

First. By means of the elevating-gear of the gun lay the gun by the autosight on the target and read the range off the arc 29, adding or subtracting therefrom, according to the state of the tide.

Second. Take out the range-curve and substitute therefor a special cam-curve, which will make the sight-bar follow the axis of the gun when the elevating-gear is worked.

Third. Put the Scott sight into its bearings at the side of the sight-bar, if there is no other telescopic sight fitted to the sight-bar.

Fourth. Set the sight to the elevation and deflection for the range.

What I claim, and desire to secure by Letters Patent of the United States, is—

1. In sighting apparatus for ordnance the combination with the gun, of a range-curve and sight carried by the gun carriage or support, means operated by the elevating-gear of the gun for actuating said range-curve so as to automatically alter the angle between the line of sight and the longitudinal axis of the gun in accordance with the range, and means for automatically adjusting the sight horizontally to allow for the "drift" of the shot,

as the range-curve is elevated or depressed, substantially as and for the purpose specified.

2. In sighting apparatus for ordnance, the combination with the gun and means for elevating said gun, of a range-curve, means operated by the elevating-gear of the gun for actuating said range-curve so as to automatically alter the angle between the line of sight and the longitudinal axis of the gun in accordance with the range, a sight-bracket pivoted to the range-curve and provided with a camway or slot, and a fixed arm with which said camway engages so as to give the sight-bracket a horizontal adjustment to allow for the "drift" of the shot as the range-curve is elevated or depressed, substantially as and for the purpose specified.

3. In sighting apparatus for ordnance, the combination with the gun and means for elevating said gun, of a standard fixed to the gun-platform, a bracket pivoted to said standard, means for adjusting the bracket in a vertical plane with reference to the standard, a range-curve and sight pivoted to the bracket, a lever pivoted to the standard, a roller carried by said lever and upon which the range-curve bears, and means connecting the lever with the elevating-gear of the gun, substantially as and for the purpose specified.

30 4. In sighting apparatus for ordnance, the combination with the gun and means for elevating said gun, of a standard fixed to the gun-platform, a bracket pivoted to said standard, means for adjusting the bracket in a vertical plane with reference to the standard, a range-curve and sight pivoted to the bracket, a lever pivoted to the standard about the same pivot as that of the bracket, a roller carried by said lever and upon which the range-curve bears, and means connecting the lever with the elevating-gear of the gun, substantially as and for the purpose specified.

5. In sighting apparatus for ordnance, the combination with the gun and means for elevating said gun, of a standard fixed to the gun-platform, a bracket pivoted to said standard, a range-curve and sight pivoted to said bracket, a lever pivoted to the standard about the same pivot as that of the bracket, a roller carried by said lever and upon which the range-curve bears means connecting said lever with the elevating-gear of the gun, and means for automatically adjusting the sight horizontally to allow for the "drift" of the shot, as the range-curve is elevated or depressed, substantially as and for the purpose specified.

6. In sighting apparatus for ordnance, the combination with the gun and means for elevating said gun, of a standard fixed to the gun-platform, a bracket pivoted to said standard, a range-curve pivoted to said bracket, a sight-bracket pivoted to the range-curve and provided with a camway or slot, a fixed arm with which said camway engages so as to give the sight-bracket a horizontal adjustment to allow for the "drift" of the shot, as the range-

curve is elevated or depressed, and means operated by the elevating-gear of the gun for actuating said range-curve so as to automatically alter the angle between the line of sight and the longitudinal axis of the gun in accordance with the range, substantially as and for the purpose specified.

7. In sighting apparatus for ordnance, the combination with the gun and means for elevating said gun, of a standard fixed to the gun-platform, a bracket pivoted to said standard, a lever pivoted to the standard about the same pivot of said bracket, a range-curve pivoted to said bracket, a sight-bracket pivoted to the range-curve and provided with a camway or slot, a fixed arm with which said camway engages so as to give the sight-bracket a horizontal adjustment to allow for the "drift" of the shot as the range-curve is elevated or depressed, a roller carried by said lever and upon which the range-curve bears, and means connecting the lever with the elevating-gear of the gun, substantially as and for the purpose specified.

8. In a sighting apparatus for ordnance, the combination with the gun and means for elevating said gun, a range-curve comprising a frame having perforations a central cylindrical space and a channeled extension at each end, a curve or cam provided with a central slot and having its ends adapted to slide in the channels in said extensions, a piston in the central cylindrical space in the frame, a spring which tends to raise said piston, a piston-rod carried by said piston and having one end adapted to engage the central slot in the curve and the other end provided with a push-piece, and adjusting-screws which engage perforations in the frame and bear upon the ends of the curve or cam, a sight carried by the range-curve frame or part carrying the range-curve, and means operated by the elevating-gear of the gun for actuating said range-curve so as to automatically alter the angle between the line of sight and the longitudinal axis of the gun in accordance with the range, substantially as and for the purpose specified.

9. In sighting apparatus for ordnance, the combination with the gun and means for elevating said gun, of a standard fixed to the gun-platform, a bracket pivoted to said standard, a range-curve pivoted to said bracket and comprising a frame having perforations a central cylindrical space and a channeled extension at each end, a curve or cam provided with a central slot and having its ends adapted to slide in the channels in said extensions, a piston in the central cylindrical space in the frame, a spring which tends to raise said piston, a piston-rod carried by said piston and having one end adapted to engage the central slot in the curve and the other end provided with a push-piece, and adjusting-screws which engage perforations in the frame and bear upon the ends of the curve or cam, a sight carried by the range-curve frame, a lever pivoted to the standard, a roller carried

by said lever and upon which the range-curve bears, and means connecting the lever with the elevating-gear of the gun, substantially as and for the purpose specified.

- 5 10. In sighting apparatus for ordnance, the combination with the gun and means for elevating said gun, of a standard fixed to the gun-platform, a bracket pivoted to said standard, means for adjusting the bracket in a vertical plane with reference to the standard, a range-curve pivoted to said bracket and comprising a frame having perforations a central cylindrical space and a channeled extension at each end, a curve or cam provided with a central slot and having its ends adapted to slide in the channels in said extensions, a piston in the central cylindrical space in the frame, a spring which tends to raise said piston, a piston-rod carried by said piston and having one end adapted to engage the central slot in the curve and the other end provided with a push-piece, and adjusting-screws which engage perforations in the frame and bear upon the ends of the curve or cam, a sight carried by the range-curve frame, a lever pivoted to the standard, a roller carried by said lever and upon which the range-curve bears, and means connecting the lever with the elevating-gear of the gun, substantially as and for the purpose specified.

pivot as said bracket, a range-curve pivoted 35 to said bracket and comprising a frame having perforations a central cylindrical space and a channeled extension at each end, a curve or cam provided with a central slot and having its ends adapted to slide in the channels in said extensions, a piston in the central cylindrical space in the frame, a spring which tends to raise said piston, a piston-rod carried by said piston and having one end adapted to engage the central slot in the curve and the other end provided with a push-piece, and adjusting-screws which engage perforations in the frame and bear upon the ends of the curve or cam, a sight-bracket pivoted to the range-curve frame and provided with a curve 50 or cam, a fixed pin or boss with which said cam engages so as to give the sight-bracket a horizontal adjustment to allow for the "drift" of the shot as the telescopic sight which moves with the range-curve is elevated 55 or depressed in a vertical plane, a roller carried by said lever and upon which the range-curve bears, and means connecting the lever with the elevating-gear of the gun, substantially as and for the purpose specified.

In testimony whereof I have hereunto set my hand, in presence of two subscribing witnesses, this 18th day of September, 1901.

LOTHIAN KERR SCOTT.
